UNITED STATES PATENT OFFICE.

JOHN W. HUDSON, OF MADISON, WISCONSIN.

AGRICULTURAL BOILER.

SPECIFICATION forming part of Letters Patent No. 229,891, dated July 13, 1880.

Application filed January 17, 1880.

To all whom it may concern:

Be it known that I, JOHN W. HUDSON, of the city of Madison, in the county of Dane and State of Wisconsin, have invented certain new and useful Improvements in Agricultural Boilers; and I do hereby declare that the following is a full, clear, and exact description of the invention, which will enable others skilled in the art to which it appertains to make and use the same, reference being had to the accompanying drawings, which form a part of this specification.

Figure 1 is a vertical sectional view of a furnace and boiler embodying the improvements in this invention. Fig. 2 is a longitudinal sectional view of the same, and Fig. 3 is a view of the removable cast-iron lining.

This invention relates to improvements in furnaces and farm-boilers; and it consists of the improvements in the construction of the same, hereinafter more fully described, and particularly pointed out in the claim.

In the accompanying drawings similar letters of reference indicate like parts of the invention.

The furnace consists of the sheet-metal casing A, provided with the cast-iron door B at the front, and the cast-iron bottom C, having the grate D and ash-pit E. A removable cast-iron lining, F, cast in one piece, is corrugated or ribbed, is open at the front, and flares up-

wardly, to conduct the heat to the bottom of the boiler G. A door, H, covers the ash-pit in front of and beneath the door B.

To make the casing A of cast-iron would cause the furnace to be very heavy and unwieldy, and when sheet metal is used without the cast-iron lining F the casing soon burns through; but by making the door B of cast-iron and the lining F of the same material, they, in conjunction with the bottom, surround the fire and protect the casing. The corrugations or ribs in the removable lining strengthen it, and its flaring form serves to direct the flame against the bottom of the boiler.

Having thus fully described my invention, what I claim, and desire to secure by Letters Patent, is—

In a furnace for farm-boilers, the sheet-metal casing A, having the cast-iron door B and the cast-iron bottom C, in combination with the removable cast-iron ribbed lining F, made in one piece and flared outwardly and upwardly, and the door H, located as described, substantially as and for the purposes set forth.

In testimony that I claim the foregoing as my own I have hereto affixed my signature in presence of two witnesses.

JOHN W. HUDSON.
